(57) **CLAIM**

The ornamental design for a front end for blaster pistol, as shown and described.

DESCRIPTION

FIG. 1 is a perspective view of a front end for blaster pistol, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a cross-sectional view taken along the line 8-8 of FIG. 6; and,

FIG. 9 is an enlarged view of portion 9 indicated in FIG. 1. The evenly broken lines depict unclaimed portions of the front end for blaster pistol; the dash-dot broken lines disclose boundaries of the isolated and enlarged views; the broken lines form no part of the claimed design.
